DESIGN FOR A HOIST ATTACHMENT FOR TRACTORS

Louis Wenger, Sabetha, Kans.

Application December 18, 1944, Serial No. 116,970

Term of patent 7 years

(Cl. D41—1)

To all whom it may concern:

Be it known that I, Louis Wenger, a citizen of the United States, residing at Sabetha, in the county of Nemaha and State of Kansas, have invented a new, original, and ornamental Design for a Hoist Attachment for Tractors, of which the following is a specification, reference being had to the accompanying drawing, forming a part thereof.

Fig. 2 is a front elevational view of the design.

Fig. 3 is a plan view of the design.

I claim:

The ornamental design for a hoist attachment for tractors, as shown.

LOUIS WENGER.
